(54) **GOLD, AMALGAM MILL FOR SPARATING
FROM ORE**

(76) Inventor: **Joseph Curtis**

Joseph Curtis

The schedule referred to in these letters Patent and making part of the same containing a description in the words of the said Joseph Curtis himself of his Improvement in the Amalgam Mill for separating Gold from the Ore.

To all to whom these presents shall come.

Be it known that I Joseph Curtis have invented certain new and useful improvements in an Amalgam Mill to take Gold from the Ore, and that the following is a full and exact description of the construction of said Machine as invented by me -

A pot or bed piece cast iron $\frac{1}{2}$ an inch thick the pot part α . 10 inches diameter and about 12 inches deep to the center where a hole $1\frac{1}{2}$ inches diameter is cut and has a bent pipe 11⁰ 1. screwed into which is fitted with a tapering female screw to receive the male screw on the end of the pipe 2. which is of sufficient length to pass through the brickwork of the furnace and this has a taper thumb screw 3. fitted in the end by the means of which the Mercury can be drawn out of the pot without disturbing the fire in the furnace 3. which is intended to be built under the Mill for the purpose of heating the mercury and thereby causing the amalgamation to be more perfect and also by building the furnace so as to throw the body of the flame on the pipe 2. and heat it to such a degree as to evaporate the mercury in the pipe and cause the Gold which has amalgamated to deposit there and as the mercury after having evaporated in the pipe will condense in its passage upwards a fresh supply of mercury will be continually running into the pipe to take the place of that evaporated

from the edge of the pot. a. a. is a plain or flange c. c. 2½ inches diameter than a descending flange d. d. 2 inches deep to this flange is riveted a cylinder of sheet iron c. $\frac{1}{8}$ of an inch thick and 1½ inches deep at the top and either side is riveted a wrought iron hoop 1 inch broad and $\frac{3}{8}$ of an inch thick from this cylinder a flange of discharge or spout f. of sheet iron 3 inches square the upper part of which is within 2 inches of the top, this spout may be contracted by means of ^{bricks of} flange ^{flange} as the quantity of water may require.

A frame of timber say 3 inches square for the upright and 2½ inches by 6 inches for the cross piece is required to support the tube g. on which the pot h. is attached for a base, this frame of timber is secured to the mill by bolts and nuts passing through the descending flange d. and the timber, and also by 2 bolts and nuts passing through the wrought iron hoop c. at the upper end of the cylinder, and timber.

Orifices of about $\frac{1}{16}$ of an inch are made in the wrought iron cap and end of the tube below the lower casting plate equaling or nearly so the sectional area of the tube to secure the bar b. in its place a wrought iron hoop not riveted M. is put inside the pot the same being $\frac{1}{16}$ of an inch thick and 2 inches deep on this rests the plate N. of 10 inches diameter and $\frac{1}{8}$ of an inch thick having a round hole in the centre of 5 inches diameter this is secured to its place by another hoop similar to M. (and in like manner as many hoops as may be required) and the whole is secured by the upper plate P. which is screwed into its place by small screws going into the pot.)

To the cast iron tube one inch from the bottom resting on a small projection in the casting on a

thin wrought iron hoop shrunk to the tube as a sheet iron plate $\frac{1}{8}$ of an inch thick and 9 inches diameter than a sheet iron hoop or sleeve $\frac{1}{8}$ inch thick and 2 inches broad than another plate similar to r. all of which and more if required are bedded on by keys or wedges.

G is a floating revolver made of fine plank 2 inches thick and 22 inches diameter the bottom of which is covered with sheet copper to keep this tube and perfectly level it is attached to a wood tube S. $1\frac{1}{2}$ inch thick and 14 inches long that fits the tube just not so tight as to prevent its rising and falling as the fluid may require in the upper end of the tube is inserted an iron box W. (a cast wheel box does as well) a groove is chiselled $\frac{1}{4}$ of an inch square lengthwise of the box W. and a wrought iron feather or key of about 14 inches long is fitted to the groove, and secured to the cast iron tube.

To the outer edge of this wooden revolver is attached a sheet iron cylinder U. $\frac{1}{8}$ inch thick and 12 inches deep to stiffen the cylinder a wrought iron hoop $\frac{1}{8}$ or $\frac{3}{8}$ inches thick and 1 inch broad is riveted inside the upper edge. The pulley No. for the band is permanently fitted with a cast iron box M. inside and projecting above the pulley say one inch which runs in the braces X. fitted in the crop beams the cast iron box can be adjusted so as to keep the tube in its place which when the quicksilver is in the pot as pressing upwards. To the cast iron tube a pipe of tin, iron or copper Y. with a turned top is inserted of sufficient length to be equal to the hydrostatic power required which for the machine here named must be 80 inches.

The quicksilver must fill the pot and say

1 inch deep on the plain or flange of 34 inches. The vessel
over which floats must have a weight of sand or water
to cause it to settle say 1/2 an inch into the quicksilver.

The Ore must be reduced to an impalpable powder
either by dry or wet process when prepared for this mill
it must be wet and conducted in a running stream
of water into the tunnel of the upper tube whence it
will find its way by its pressure through the orifices
in the lower end of the tube and through the quick-
silver to the discharge Spout. f. in the direction of
the arrows.

The intent of giving the centre part a circu-
lar motion is to cause a more thorough distribution of
the ore and water among the Mercury. The quality
of the Ore to the measure of water depends on the earthy
State of the ore.

The oscillations of the mill may be supposed
to average 16 a minute, but all depends on the quality
of the ore.

And I Joseph Curtis do hereby claim
as my invention an improvement in the amalgam
mill the application of heat to the ore in passing
through the stratum of quicksilver by making the
fire glide around or beneath the vessel in which the
process is carried forward in manner aforesaid or in
any other manner preferred

Witness
